DESIGN FOR A FEED BOWL FOR DOMESTIC ANIMALS

Ian M. Robertson, Chicago, Ill.

Application July 15, 1936, Serial No. 63,871

Term of patent 7 years

To all whom it may concern:

Be it known that I, Ian M. Robertson, a citizen of the United States, residing at Chicago, in the county of Cook and State of Illinois, have invented a new, original, and ornamental Design for a Feed Bowl for Domestic Animals, of which the following is a specification, reference being had to the accompanying drawing, forming part thereof.

In the drawing, Figure 1 is a top plan view of the feed bowl; and,

Figure 2 is a side elevational view of the feed bowl of my design.

I claim:

The ornamental design for a feed bowl for domestic animals, as shown.

IAN M. ROBERTSON.
